UNITED STATES PATENT OFFICE.

WILLIAM O'DONNELL, OF OKLAHOMA, OKLAHOMA.

PILING.

1,245,373.

Specification of Letters Patent. Patented Nov. 6, 1917.

Application filed September 20, 1915. Serial No. 51,578.

To all whom it may concern:

Be it known that I, WILLIAM O'DONNELL, a citizen of the United States, residing at Oklahoma, in the county of Oklahoma and State of Oklahoma, have invented certain new and useful Improvements in Piling, of which the following is a specification, reference being had to the accompanying drawings.

10 The invention pertains to improvements in piling.

An object is to provide improved means for sinking the piling.

15 Other objects and advantages of the invention will be set forth in the ensuing description.

One embodiment of the invention in practical form is shown by the accompanying drawings.

20 Figure 1 shows a river-bed and shows four of the improved piling which have been driven to grade and are supporting trestle-work which carries a traveling crane for handling and sinking additional piling.

25 Fig. 2 is a similar elevation view showing how the sections of piling are handled and how certain water supply connections are made.

Fig. 3 is an enlarged plan view of a 30 clamp.

Fig. 4 is a similar view of a clamp and a pivoted arm.

Fig. 5 is a sectional view, on still larger scale, of the lower end of the improved 35 piling.

Fig. 6 is a plan view, on still larger scale, of a boring foot at the lower end of the piling.

Fig. 7 is an elevation view of the boring 40 foot and a fragment of a shaft which drives it.

Like characters of reference designate like parts in all the figures of the drawings.

In this invention the piling includes an 45 outer tube or casing 10 of any suitable material, such, for example, as common large gas pipe or boiler-iron, according to the size of piling required; and this casing may be of any suitable shape in cross-section, 50 such, for example, as round, hexagon, or octagon.

This casing 10 may also be of a thickness adapted to support its load by its own resistance to bending or crushing strain, or, 55 after being sunk to place, it may be filled

with any suitable material, such, for example, as concrete.

In providing for sinking the casing 10, a boring foot 11 is arranged to revolve in its lower end and bore or drill its way 60 downward into the sand or rock.

This boring foot 11 is provided with an axial neck 12 terminating in a head 13, and the neck and head are revolvably embraced by a separable bearing block 14 which 65 tightly fills the lower end of the casing 10.

This bearing block 14, which must be in two parts for assemblage with the head and neck of the boring foot 11, is held together by the embracing lower end of the casing 70 10, but for greater convenience in assembling the parts an iron band 15 may first be put on the lower end of the block hot and be shrunk tight, the casing resting on said band.

To drive the boring foot 11, a shaft 16 is extended down through the axial center of the casing 10 and has its squared lower end inserted in the head 13 of said foot.

In arranging to drive this shaft 16, its 80 upper end is provided with a gear-wheel 17 above the upper end of the casing 10, and this gear-wheel is driven by a worm pinion 18 on the shaft 19 of a suitable motor 20.

The motor 20 may rest on a platform 21 85 which is attached rigidly to the casing 10, and said platform is supported by corner braces 22 which are in turn supported by two bands 23 which clamp removably around the casing 10.

90 In making ready to sink the piling, the boring foot 11 and driving shaft 16 are put in place in the casing 10; the supporting platform 21 also being attached to the upper end of said casing with the motor 20 in 95 place thereon and operatively connected to said shaft 16; all this being done while the casing 10 lies horizontal and in position for convenient assemblage.

By use of the boom 24 and tackle 25 of 100 the crane 26, the casing 10 is raised to vertical position as shown in Fig. 1, the tackle-block 27 being hitched to the four corners of the platform 21 by four rods or cables 28.

105 With the casing 10 in vertical position, the motor 20 is started and the boring foot 11 begins to bore downward under the weight of the casing and attached parts.

To remove the material resulting from the boring operation, the boring foot 11 and 110

its neck and head are bored out axially, as at 29, and the driving shaft 16 is made tubular.

5 A pipe 30, leading from a pumping engine 31 or other source of water supply, has one of its branches, 32, connected to the upper end of the tubular shaft 16, this connection comprising a portion of flexible hose 33 which attaches to said shaft by a swiveled goose-neck 34; and by forcing water down said shaft 16 the dirt, sand, and other material cut loose by the boring foot 11 is washed up on the outside of the casing 10 as shown in Fig. 1.

15 A stuffing-box 35 to prevent undue leakage of water upward past the lower end of the driving shaft 16 may be provided and secured to the upper surface of the bearing block 14.

20 A little concrete 36 may be poured around the stuffing-box 35, if desired, and will tend to hold said stuffing-box still.

To prevent the casing 10 from being revolved by the action of the boring foot 11, 25 a clamp 37, shown in Fig. 4, may embrace said casing, a long arm 38 being pivoted to this clamp on a horizontal axis to allow the sinking movement of the casing 10, and having its outer or free end attached to any 30 suitable fixed object.

After once starting to bore a piling downward into the ground or into sand or rock the forced flow of water down through the boring foot 11 should not stop, even though 35 the revolution of the foot and the boring be stopped for a time.

But since in adding another section of casing 10 to that already sunk it is necessary to uncouple the goose-neck connection

40 34 at the top of the shaft 16 and remove the gear-wheel 17, platform 21, and other parts, an additional means of maintaining a forced flow of water down through the boring foot must be provided.

45 In providing this means, a pipe 39 is led down the interior of the casing 10 alongside the shaft 16 and into a port 40 in the bearing block 14, and this port 40 is arranged to be in communication with at least two of a

50 series of ports 41 which lead down through the head 13 of the boring foot and into communication with the central bore 29 thereof.

The second branch, 42, of the pipe 30 is connected to the upper end of the pipe 39 55 by a flexible hose 43, so that while tubular shaft 16 is out of service water is supplied to the boring foot 11 through said pipe 39.

A check-valve 44, adapted to prevent back flow of water up the shaft 16, is arranged in 60 the head 13 of the boring foot 11 and adapted to seat against said shaft; and likewise a check-valve 45, to prevent back flow of water up the pipe 39, is arranged in the port 40 and adapted to seat against the lower end 65 of said pipe.

In removing the platform 21 from the top of the sunken section of casing 10, the openings 46 in its supporting clamps 23, best shown in Fig. 3, pass over the horizontal portion 47 at the upper end of the pipe 39; and after said platform has been mounted on the new section and said new section suspended over the sunken section as shown in Fig. 2, water supply may be reestablished through the shaft 16 and the hose 43 and 75 pipe connection 47 uncoupled from the upper end of the pipe 39 before bringing the two sections together.

There will be no trouble in coupling a new section of the shaft 16 and a new section of 80 the pipe 39 to the sections sunk with the casing 10.

After the casing 10, comprising one or a number of sections, has been sunk to grade or to the desired depth, the platform 21 and 85 attached parts may be removed, as may also the shaft 16 and the pipe 39; and the casing 10 may then be filled entirely to the bottom with concrete or any substance adapted to strengthen and reinforce said casing. 90

The boring foot 11, together with its bearing block 14, remains as a permanent footing for the casing 10.

It will be seen that there is provided: a piling having a revolvable point which will 95 bore its way downward without the necessity of revolving the entire piling; that there is provided means for maintaining a continued and forced supply of water through the piling and through its revolvable point 100 to wash a clearance for the piling; and that the objects of the invention are fully attained.

Having thus described the invention, I claim:—

1. In piling, a tubular body having at its lower end a boring member, a tubular shaft leading down the interior of the body and operatively engaging said boring member, means for forcing water down said shaft to 110 remove the material resulting from the action of the boring member, and means for supplying water to the boring member during the time the shaft is out of service.

2. In piling, a tubular body embracing at 115 its lower end a bearing, a boring foot arranged below said bearing and having an axial neck extending up into said bearing, said foot and neck having an axial port opening downward onto the boring face of 120 said foot, a tubular shaft extending down the interior of the tubular body and operatively engaging said port to drive the foot, the bearing having a port, the neck of the foot having ports leading from its central 125 port into communication with the port of the bearing, and a pipe leading down the interior of the tubular body to the port of the bearing.

3. In piling, a tubular body embracing at 130

its lower end a bearing, a boring foot arranged below said bearing and having an axial neck extending up into said bearing, said foot and neck having an axial port 5 opening onto the boring face of said foot, a tubular shaft extending down the interior of the tubular body and operatively engaging the port to drive said foot, a check-valve arranged in the port and adapted to seat against the lower end of the shaft, the bearing 10 having a port, the neck of the foot having ports leading from its central port into

communication with the port of the bearing, a pipe leading down the interior of the tubular body into the port of the bearing, and 15 a check-valve arranged in the port of the bearing and adapted to seat against the lower end of said pipe.

Witness my hand this 16 day of September, 1915.

WILLIAM O'DONNELL.
